UNITED STATES PATENT OFFICE.

WILFRID STONESTREET, OF NASHVILLE, TENNESSEE.

GAME.

1,148,060.

Specification of Letters Patent. Patented July 27, 1915.

Application filed January 27, 1915. Serial No. 4,743.

To all whom it may concern:

Be it known that I, WILFRID STONESTREET, a citizen of the United States, residing at Nashville, in the county of Davidson and State of Tennessee, have invented certain new and useful Improvements in Games, of which the following is a specification.

This invention contemplates an improved game or puzzle and has as its primary object 10 to provide an article of this character which, in its solution, will require the movement or shifting of game pieces to simulate the offensive movements of opposing forces in war.

15 The invention has as a further object, and more specifically, to provide a game employing certain game pieces which will be substitution upon the board designated by the nationality having a particular assigned location upon the board designed by the national flag of such men; to further provide other game pieces representing men of certain different nationalities constituting allies opposing said first mentioned men, each 20 nationality of the allies to also have a particular assigned location upon the board designated by the national flag of each ally and wherein the specific attainment of the game will be to so move the game pieces upon the 25 board that all of the men of the first mentioned nationality, or, on the other hand, all of the men of the allies will occupy the positions of the opposing force.

A still further object of the invention is 30 to provide a game board so constructed and having the respective positions of the opposing men so formed and arranged, that the shifting of the several game pieces to accomplish the purpose set forth, will be rendered relatively difficult to thus enhance the interest incident to the playing of the game or solution of the puzzle.

Other and incidental objects will appear as the description proceeds and in the drawings wherein I have illustrated the preferred embodiment of the invention and wherein similar reference characters designate corresponding parts through the several views. Figure 1 is a perspective view of my improved game showing the several game pieces in their respective positions, and Fig. 2 is a top plan view more particularly illustrating the construction of the game board.

50 In carrying out my invention, I employ a game-board indicated as a whole in the drawings by the numeral 10. This game-

board is preferably formed from relatively light sheet metal although any other suitable material may be employed, if found more desirable. As illustrated, the game-board is 60 preferably circular and includes a floor or bottom wall 11 which is surrounded at its periphery, by an annular upstanding flange or side wall 12.

Arranged upon the bottom wall 11 in inwardly spaced relation to the wall 12 is an annular upstanding flange or partition wall 13 defining therebetween and the wall 12, an annular runway 14. The wall 13 is cut away preferably, at quadrantly spaced points to 70 provide passages or openings 15 communicating with the runway 14 and the central portion of the game board.

Medially disposed upon the bottom wall 11 are a plurality of spaced upstanding 75 walls 16 which are, as best shown in Fig. 2 of the drawings, relatively short when considered in connection with the diameter of the game board and which are arranged parallel with each other. Intersecting the walls 16 medially thereof, is a transversely extending partition wall 17 which, as will be observed, defines, in connection with the walls 16, oppositely disposed pairs of reversely facing compartments or positions 18 and 19 respectively.

Particular attention is now directed to the fact that the intermediate one of the walls 16 is arranged in a plane intersecting a diametric line passing medially through the 90 adjacent opening 15 disposed opposite to said walls, while the openings 15 arranged in a plane at right angles to the said first mentioned openings are disposed opposite the sides of the terminal walls 16. The purpose of this arrangement will presently appear.

Arranged within the wall 13 to extend radially therefrom at quadrantly spaced points, are pairs of spaced upstanding walls 100 20, each pair of walls being arranged parallel to each other and the several walls defining positions or compartments designated 21, 22, 23, and 24 respectively.

It will be noted that the several compartments just previously referred to are each arranged medially between adjacent openings 15 and are thus arranged at an acute angle to the adjacent compartments 18 and 19 respectively. The purpose of this construction will also presently appear.

Preferably secured within the angle be-

tween the wall 13 at one of the adjacent walls 20 of each compartment is a vertically arranged pin or staff 25, which may be held in position in any suitable manner and upon the upper terminal of which is mounted a laterally projecting flag, the several flags being designated respectively by the numerals 26, 27, 28, and 29. It will be noted that the flags referred to are supported in spaced relation above the upper edges of the walls 12 and 13 and are each preferably formed from a single strip of metal bent at one terminal to embrace the supporting staff. The flag 26 is colored in any suitable manner to represent a British flag. The flag 27 is similarly colored to represent a French flag, and the flags 28 and 29 are suitably colored to represent Russian flags. Preferably arranged within the angle defined by the intersecting walls of one of the compartments 18 is an upstanding staff 30 which is mounted in a manner similar to the staffs previously described and is of like character. The staff 30, adjacent the upper terminal thereof is provided with a flag 31, similar in construction to the flags previously described and which is suitably colored to represent the German flag.

In connection with the game-board thus described, I employ a plurality of movable game pieces 32, eight of which are employed. The game pieces are all similar in construction being each in the nature of a sphere which may be formed of any suitable material and in this connection, it may be stated, that ordinary marbles may be used.

Four of the game pieces are of like color, preferably blue and are to be known as the Germans and are intended to normally occupy the positions 18 and 19 beneath the German flag 31. Two other of the game pieces are also of like color, preferably white, and are to be known as the Russians. These white game pieces are normally intended to occupy the positions 23 and 24 beneath the Russian flags 28 and 29. The remaining two of the game pieces are also of like color preferably red, and are intended to indiscriminately normally occupy the positions 21 and 22 beneath the British and French flags 26 and 27, respectively.

Attention is now directed to the fact that no two game pieces can occupy any one position at the same time while the runway 14 is of such width that the game pieces cannot pass each other therein.

In use, the several game pieces will be disposed upon the game board or rolled upon the bottom wall 11 thereof as the game board is manipulated or tilted within the hands of the operator, the object of the game or puzzle being to so move the game pieces through the manipulation of the game board, that either the game pieces representing the Germans which, as will be

remembered, are identified by the color blue, will occupy the positions of the Russians, French and British, which latter positions shall be referred to as the allies' positions, or on the other hand, that the game pieces representing the allies which may also be readily distinguished by their representative colors, will occupy the positions of the game pieces of the Germans. If the game-board can be so manipulated as to cause the game pieces of the allies to occupy the positions of the game pieces of the Germans before the game pieces of the Germans may have moved to occupy the positions of the allies, the puzzle will be considered to have been solved and the game won in favor of the allies. On the other hand, if the game board can be so manipulated as to cause the game pieces of the Germans to occupy the positions of the game pieces of the allies before the game pieces of the allies may have moved to occupy the positions of the game pieces of the Germans, the puzzle will be considered to have been solved and the game won in favor the Germans.

In forming the several compartments of the game board so that no two game pieces can occupy any one position at the same time, it will be seen that when the game board is manipulated in an attempt to solve the puzzle, all of the game pieces not actually within the compartments will remain free to roll about the board and thus render the solution of the puzzle more difficult. It will further be seen that should some certain game piece which it were desired to roll into a particular position, to become disposed with other game pieces upon each side thereof within the runway 14, it would be necessary to so manipulate the board that all of such game pieces within the runway would roll within the runway to a position where the particular game piece desired would come opposite one of the openings 15 in order that it might be then selected from the remaining game pieces within the runway. Obviously, to thus manipulate the game board will make the solution of the puzzle very difficult and the purpose of making the runway 14 so that the game pieces cannot pass therein will, therefore be clear.

It is further to be observed that no two game pieces can pass through one of the openings 15 at the same time. This arrangement tends to increase the difficulty of solution of the puzzle and in this connection, particular attention is directed to the fact that no one of the openings 15 is directly in alignment with any one of the several positions of the game-board. A game piece entering through one of the openings 15 opposite the ends of the walls 16 will normally strike the ends of the said walls to

be deflected thereby away from the adjacent positions 18 and 19, while a game piece entering through the oppositely disposed openings 15 at right angles to the first mentioned openings 15, will strike the sides of the terminal walls 16. Furthermore, as will be best seen upon reference to Fig. 2 of the drawings, no two of the several positions of the board are in alinement with each other. As will be readily understood, this peculiar disposition of the several positions relative to each other and of the openings 15 relative to the positions, will make the solution of the puzzle quite difficult to thus render it the more interesting since it will not be possible in the manipulation of the game-board to roll a game piece in a straight line from one position to another or to roll a game piece in a straight line from the runway 14 through one of the openings 15 to enter one of the said positions. The purpose of the relative arrangement of the several positions of the board as previously referred to, will therefore be clear.

Having thus described my invention, what I claim and desire to secure by Letters Patent is:—

1. A device of the character described including a game board, a wall arranged upon the board and defining a runway, said wall having a plurality of spaced passages formed therein, pairs of spaced walls defining positions adjacent said first mentioned wall, the said positions being arranged in staggered relation to said passages, spaced walls defining a plurality of positions spaced from said first mentioned wall, and a plurality of game pieces movable upon the board within said runway, said game pieces being adapted for movement through said passages to be disposed in said positions.

2. A device of the character described including a game board, a wall defining a substantially annular runway upon the board, the said wall having quadrantly spaced passages formed therein, walls defining quadrantly spaced positions adjacent said first mentioned wall, the positions being arranged in staggered relation to said passages, walls defining oppositely disposed pairs of reversely facing positions spaced from said first mentioned wall, and a plu-

rality of game pieces each adapted to occupy one at a time one of said positions and disposed for movement upon the board through said passages to enter the runway.

3. A device of the character described including a game board, a wall defining a substantially annular runway upon the board, the said wall having quadrantly spaced passages formed therein, radial walls defining quadrantly spaced positions upon the board adjacent said first mentioned wall, the said positions being arranged in staggered relation to said passages, a plurality of intersecting walls defining oppositely disposed pairs of reversely facing positions medially of the board, the ends of certain of said last mentioned walls being presented toward certain of said passages, and a plurality of game pieces adapted to occupy said positions and movable upon the board through said passages to enter the runway.

4. A device of the character described including a game board, a wall defining a runway upon the board, said wall having a passage formed therein, walls defining a position adjacent said first mentioned wall, walls defining a position spaced from said first mentioned wall, a flag identifying said first mentioned position, a flag identifying said last mentioned position from the first mentioned position, and a plurality of game pieces identified each with one of said flags and adapted to occupy said positions, said game pieces being movable upon the board through said passage to enter the runway.

5. A device of the character described including a game board, a wall defining a runway upon the board, said wall having a passage formed therein, walls defining a position adjacent said first mentioned wall, walls defining a position spaced from said first mentioned wall, an identifying flag arranged adjacent said first mentioned position, an identifying flag arranged adjacent said last mentioned position, and a plurality of game pieces each identified by a color with one of said flags and adapted to occupy said positions, said game pieces being adapted for movement upon the board through said passage to enter the runway.
